DESIGN FOR A CUP OR SIMILAR ARTICLE

Sasha Katchamakoff, Los Angeles, Calif.

Application October 8, 1935, Serial No. 58,884

Term of patent 7 years

To all whom it may concern:

Be it known that I, Sasha Katchamakoff, a subject of the King of Bulgaria, residing in the city of Los Angeles, county of Los Angeles and State of California, have invented a new, original, and ornamental Design for a Cup or Similar Article, of which the following is a specification, reference being had to the drawing, forming a part thereof.

In the drawing, Figure 1 is a side elevational view of the cup or similar article, showing my design;

Figure 2 is an end elevational view; and

I claim:

The ornamental design for a cup or similar article, as shown.

In witness whereof, I affix my signature.

SASHA KATCHAMAKOFF.
